CLAIM

The ornamental design for a multifunction printing machine, as shown and described.

DESCRIPTION

FIG. 1 is a perspective view of a multifunction printing machine in accordance with the present invention;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken lines in the drawings depict environmental subject matter, are for illustrative purposes only and form no part of the claimed design.
